FIG. 1

FIG. 3

FIG. 2

FIG. 4

FIGURE 1 is a perspective view of a liquid storage tank showing our new design;

FIGURE 2 is a side elevational view thereof;

FIGURE 3 is a cross-sectional view thereof taken on line III—III of FIGURE 2; and

FIGURE 4 is a cross-sectional view thereof taken on line IV—IV of FIGURE 2.

The dominant features of my design reside in the portions shown in full lines.

The characteristic features of the design reside in the projecting spaced apart sloping exposed beam ends in combination with the flat roof and plinth portion.

We claim:

The ornamental design for a liquid storage tank, as shown and described.
